UNITED STATES PATENT OFFICE.

CONSTANTINE RUGGABER, OF SAVANNAH, GEORGIA, ASSIGNEE OF ONE-THIRD TO
WILLIAM J. RUGGABER, OF SAVANNAH, GEORGIA.

METALLIC RAILROAD-TIE.

1,283,923.

Specification of Letters Patent. Patented Nov. 5, 1913.

Application filed June 4, 1913. Serial No. 238,148.

To all whom it may concern:

Be it known that I, CONSTANTINE RUGGABER, a citizen of the United States, and a resident of Savannah, in the county of Chatham and State of Georgia, have invented certain new and useful Improvements in Metallic Railroad-Ties, of which the following is a specification.

My invention is an improvement in metallic railroad ties, and has for its object to provide a tie of the character specified, having new and improved means for rigidly connecting the rails to the tie.

In the drawings:

Figure 1 is a top plan view of the improved tie, with one rail in place;

Fig. 2 is a longitudinal section;

Fig. 3 is a section on the line 3—3 of Fig. 2, looking in the direction of the arrows adjacent to the line;

Fig. 4 is a perspective view of one of the sections of the inner lock;

Fig. 5 is a similar view of one of the sections of the outer lock.

In the present embodiment of the invention the tie 1 is composed of metal, pressed or otherwise made to shape, the body of the tie consisting of a top and integral ends and sides; and the bottom of the tie is open in order that the tie may seat on the road bed and that there will be no tendency to creep or move longitudinally of the rail.

Near each end of the tie is a transverse groove or countersink 2, the said groove being at the location of the rails 3 when the rails are in place and at each side of each groove there are openings 4 and 5, respectively, the opening 4 being at the inner side of the groove and the opening 5 at the outer side.

A locking device is provided for the inside of each rail, for preventing inward movement of the rail and for preventing upward movement of the rail. Each of these locks comprises a section 6 and a section 7. Each of these sections has an overlying lip 8, the lip of the section 6 engaging over the base flange of the rail, while the lip of the section 7 engages the upper face of the tie.

It will be noticed, referring to Fig. 2, that the depth of the groove 2 is approximately that of the thickness of the rail base so that

when the rail is in place the upper surface of the base will be approximately flush with the upper surface of the tie. The section 6 of the lock has a lip 9 which engages beneath the top of the tie at the groove, and the section 7 has a rounded lip 10 which serves the same purpose at the opposite side of the opening 4.

It will be noticed, referring to Fig. 2, that the opening 4 is of sufficient width to permit the passage of the lip 10, the opening extending slightly beneath the base flange of the rail at its outer end when the rail is in place. This permits the sections 6 and 7 to be inserted and the rail to be subsequently moved to its required operative position and then secured by the outer lock.

The outer lock consists of similar sections 11. Each of these sections has in its outer wall a transverse groove 12, of a depth and width to receive at one side the top of the tie at the edge of the opening 4 and at the other side the top of the tie and the base flange of the rail.

The sections have normally some space between their adjacent faces and they are adapted to be forced apart to lock them by means of a wedge shaped key 14. This key, which has a square head, as shown, is split at its lower end and it will be obvious that when it has been forced between the sections the split ends will spring apart, thus locking the key in place.

The size of the opening 5 is such that the sections of the outer lock may be inserted through the opening and when forced apart by the key they will be firmly locked in place by the opening. The rails are thus always held at gage.

If desired, the improved tie may be filled with concrete or the like, and in any event it is filled with the material of the road bed to anchor it in place.

I claim:

A metallic railroad tie having transverse grooves on its upper surface for the seating of the rails, and of a width and depth to receive the base flanges of the rails, said tie having openings at each side of the groove for receiving locks to lock the rails to the tie, and a lock in each opening, each of the locks consisting of similar sections having transverse grooves for receiving the edges of

base flanges and the edges of the openings, the sections at the outer sides of the rail being spaced apart from each other when the edges of the openings are seated in the cove, and a wedge shaped or tapering key engaging between the sections to force them apart, the key being split at its small end

and resilient to form a lock for the same by the springing apart of the split ends after the key has been inserted.

CONSTANTINE RUGGABER.
